UNITED STATES PATENT OFFICE

2,461,287

PACKING RETAINER FOR JOURNAL BOXES

Magnus Lagreid and John Henry McGuire,
Minneapolis, Minn.

Application June 7, 1945, Serial No. 598,060

5 Claims. (Cl. 308—89)

1

In conventional practice, railway cars, or the trucks of railway cars, are borne on axle journals, each of which is received in a journal box equipped with a journal bearing resting on the journal and held in place in the journal box by a wedge. The journal and the bearing are lubricated by a packing of oiled waste carried in the lower portion of the journal box in contact with the under surface of the journal. The packing should be loose enough to hold the maximum of oil consistent with full wiping contact with the lower surface of the journal to continuously lubricate it as the journal revolves. But the waste must not get between the journal and the bearing, for in that position it impairs or prevents proper lubrication and causes what car men call "waste grab," resulting in a hot box.

The principal object of this invention is to provide a packing retainer that will confine the packing to its proper sphere, within suitable limits of movement when the motion of the journal is reversed, and will effectively collect all the loose and short ends of the packing and prevent their being carried up to the edges of the journal bearing.

Generally speaking, this is accomplished by providing a packing retainer having side pieces to overlie the packing at each side of the journal, a front piece connecting the side pieces and the cover to overlie the packing beyond the collar on the journal, and a post rising from each side piece to a point adjacent to the top of the journal box. This retainer floats with the packing and allows the packing to move with each reversal of rotation of the journal, as it should, to prevent or break up glazing, but it retains the packing within the limits set by the side pieces coming in contact with the lugs inside of the journal box and the posts striking against the top of the journal box. The particular arrangement here disclosed collects all loose and short ends of the packing on the side pieces and cover plate, from whence they are easily removed.

In the accompanying drawings, Fig. 1 is a perspective view of a journal box equipped with a retainer according to this invention, a portion of the box being broken away to show the parts on the interior;

Fig. 2 is a perspective view of the retainer removed from the journal box and reversed end to end with respect to Fig. 1;

Fig. 3 is a longitudinal section through the journal box showing the journal, the bearing, the wedge, and the retainer in elevation; and

Fig. 4 is a half end view and half transverse vertical section of the journal box and associated parts shown in Figs. 1 and 3.

In Figs. 1, 3, and 4, the journal box indicated generally by 10 is a 5" x 9" A. A. R. standard freight car journal box, details of which may be

2

found in Car Builders' Cyclopedias, 1943, pages 1163 and 1164. The journal 11 has the usual collar 12 at its outer end. Resting on the journal is the journal bearing 13 having projections 14 which contact lug 15 on the inside of the journal box to limit the inward movement of the bearing.

The top of the bearing has polygonal surfaces 16 adapted to be received within corresponding surfaces 17 on the under side of a journal bearing wedge 18 provided with surfaces 19 contacting with the inner faces of the lugs 15 to limit the lateral motion of the wedge within the journal box. Outward motion of the wedge is limited by its end coming in contact with downwardly directed lugs 20 at the front of the journal box, and inward movement of the wedge is limited by the shoulder 21 at the inner end of the bearing.

The journal box is packed with an oily material, usually oil soaked waste 22, which fills the lower portion of the journal box up to about the middle or horizontal diameter of the journal. As the journal rotates, the waste continually wipes the surface of the journal presented to it, and thus continually supplies it with the thin layer or coating of oil necessary to lubricate the adjacent surfaces of the journal and the bearing.

The details of all the things heretofore mentioned and others common to journals and journal box arrangements are familiar, and it is deemed sufficient to merely refer to the Car Builders' Cyclopedias, above mentioned, without further description.

The preferred form and construction of a packing retainer embodying this invention is best shown in the perspective view (Fig. 2). It includes two side pieces, generally indicated by 24, connected at their front ends by a front piece 25. They are here shown, and preferably are, of angle section with the flanges 26 and 27 arranged vertically and the flanges 28 and 29 horizontally. The angle section may be either rolled or pressed metal, and in the present construction portions of the horizontal flanges are cut away to allow for the corner bends 30 at the juncture of the side and front pieces, and when the adjacent faces thus formed are brought together they are welded as indicated at 31, producing what for want of a better term may be called a 'U-shaped frame. A cover plate 32 extending between the side pieces 24 adjacent to the front piece is welded on the horizontal flanges 28.

Inwardly with respect to the cover plate the flanges 28 are cut away at 34 to provide clearance for the collar 12 on the end of the journal.

Posts 33 have their lower ends welded to flanges 26 of the side pieces 24 and extend upwardly toward the top of the journal box.

As an example of specific construction that has been found satisfactory for this size and type of journal box, the retainer shown in the drawings

is $11\frac{1}{2}$ " long and $7\frac{5}{8}$ " wide. The side and front pieces are made from $\frac{3}{4}$ " x $\frac{3}{4}$ " by $\frac{3}{32}$ " angle. The cover is made from $1\frac{1}{2}$ " x $\frac{1}{4}$ " bar stock. The post is from $1"$ x $\frac{1}{8}$ " bar stock, and the notches 34 are $\frac{1}{8}$ " deep by $1\frac{1}{4}$ " in length. Of course, suitable variations will readily be made by others to suit particular conditions.

From the drawings, it will be seen that the side pieces 24 overlie the packing at each side of the journal, and they are so related to the side walls of the box that neither piece can at any time come in contact with the journal. But the upper edge of each side piece may come in contact with the lower portion of the corresponding lug 15 on the inside wall of the journal box to limit its upward movement.

The posts 33 rising from the side pieces 24 to points adjacent to the top of the journal box clear the sides of the journal box and the sides of the journal bearing and journal bearing wedge, and are thus free to move within the limits of the allowable dimensions.

The front piece 27 and the associated cover plate 32, which obviously may be made in one, overlie the packing outwardly with respect to the collar 12 on the end of the journal, leaving clearance, as shown in Figs. 1 and 3, for access to the packing 22 for spooning and adjusting.

Assuming the journal box to be properly packed with just the right amount of oil waste, the retainer is inserted to the position shown in Figs. 1, 3, and 4 overlying the packing, where it floats with the packing and allows the packing to move within the clearance provided, as the occasion of service requires, due to the rotation of the journal and the reversal of that rotation. Constructed as described, it has just sufficient weight for the purpose without putting enough pressure on the packing to interfere with proper operation. If the packing starts to roll up in the back of the box, it will raise the corresponding side piece 24 until the upper edge of the flange 26 comes against the corresponding lug 15, when no further rolling of the packing will be permitted. If the packing starts to roll up in front, it will raise the corresponding side piece 24 until the post 33 carried by it comes against the top of the journal box, when no further rolling will be permitted.

Experience in actual use with the construction here shown reveals the fact that all loose and short ends of the packing that get free from the mass collect upon the horizontal flanges 28 and the cover plate 32, from which they are easily removed from the box, and it seems clear that the packing as a whole remains cleaner and lasts much longer than would be the case without the retainer.

The retainer is always free and can be easily inserted or removed. The recess 35 in the top of the box just behind the lugs 20 affords sufficient space for the upper end of the posts 33 to let the notched portions 34 of the side pieces 24 clear the collar 12 as the retainer is moved into or out of position, which operation is very easily accomplished without tools.

In this connection, attention is directed to the curved inner end portions 36 of the side pieces 24, which are so formed to prevent picking up the packing as the retainer is inserted or removed from its position in the journal box. The curve

is here shown as chiefly in the horizontal flange 28, but may be made by an appropriate bend in the angle section as a whole followed by removing the upper corner of the vertical flange 26.

We claim:

1. In a packing retainer for journal boxes, two spaced side pieces of angle section with their horizontal flanges directed toward each other and their vertical flanges directed upwardly from the outer edges of the horizontal flanges, a front piece connecting the side pieces, a cover plate between the side pieces adjacent to the front piece, and a post extending upwardly from each side piece behind the cover plate.

15 2. For use in a journal box having inwardly directed lugs at each side, a journal bearing therein engaging the lugs, a journal on which the journal bearing rests and lubricated packing in the bottom of the box in contact with the journal, a packing retainer comprising a forked frame having side pieces of angle section connected at their front by a front piece, a front cover between the side pieces and depressed below the upper edges of the adjacent portions of the front and side pieces, and a post extending upwardly from each side piece at the rear of the cover.

20 3. For use in a journal box having inwardly directed lugs at each side, a journal bearing therein engaging the lugs, a journal on which the journal bearing rests and lubricated packing in the bottom of the box in contact with the journal, a packing retainer comprising a forked frame having side pieces connected at their front by a front piece, a cover between the side pieces adjacent to the front piece below the level of the upper edges of the adjacent portions of the front and side pieces, and a post extending upwardly from each side piece at the rear of the cover plate.

25 4. In a packing retainer for journal boxes, a generally U-shaped frame comprising two spaced side pieces having horizontally disposed flat portions connected at one end by a front piece and each having its opposite end turned upwardly to provide a flat upturned nose to prevent picking up packing in the journal box as the frame is slid endwise into the journal box, and a post extending upwardly from each side piece between the front piece and said upturned nose.

30 5. In a packing retainer for journal boxes, a generally U-shaped frame comprising two spaced side pieces of angle section with their horizontal flanges directed toward each other, a front piece connecting the side pieces at one end of each, and the opposite ends of the horizontal flanges of the side pieces being turned upwardly to prevent picking up packing in the journal box as the frame is slid endwise into the journal box.
